Inventor,
Samuel Armstrong,
by O. Drake, Atty.

UNITED STATES PATENT OFFICE.

SAMUEL ARMSTRONG, OF NEWARK, NEW JERSEY.

METAL PACKING FOR PISTON-RODS.

SPECIFICATION forming part of Letters Patent No. 274,165, dated March 20, 1883.

Application filed January 20, 1883. (No model.)

To all whom it may concern:

Be it known that I, SAMUEL ARMSTRONG, a citizen of the United States, residing at Newark, in the county of Essex and State of New Jersey, have invented certain new and useful Improvements in Metal Packings for Piston-Rods; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The object of this invention is to provide a more durable and efficient packing for piston-rods, and one in which allowance is made for the lateral vibration of the rod when the same is out of line.

The invention consists in the combinations and arrangements of parts, substantially as will be hereinafter set forth, and finally embodied in the claims.

Referring to the accompanying drawings, in which similar letters of reference indicate like parts in each of the several figures, Figure 1 is a side elevation of a stuffing-box with a series of rings and other mechanism embodying my improvements, said parts being broken away to show a sectional view thereof. Fig. 2 is a plan of an end ring having sockets therein: Fig. 3 is a plan of a bar or plate adapted to have one end arranged in one of said sockets. Fig. 4 is a side view of an inner and outer ring in engagement, and Fig. 5 is a plan of another end ring receiving the other end of the before-mentioned bar.

In said drawings, *a* is a stuffing-box as ordinarily arranged on an engine-cylinder, said cylinder having the ordinary studs, *b*. Within said box are arranged the various parts, as will be hereinafter described. Against the head of the stuffing-box is placed a spring, *s*, preferably spiral in form. Next in order are arranged the solid ring *o*, a series of inner and outer rings, *n m*, and the solid ring *e*, which bears against the plate *d*. Said solid or uncut ring *o* may be provided with a flange, *p*, which projects inward toward the head of the box, and forms a socket adapted to receive the spring and hold the same from contact with the rod. Said ring is also formed to allow the

passage of steam from the cylinder into the forward part of the box. Said passage may be gained by forming apertures *r* in the said ring. The rings *m n* illustrated in Figs. 1 and 4 are right angular when viewed in section, and can be thus manufactured more cheaply than when beveled. The inner ring bears directly on the rod and takes the wear therefrom. 55 The outer or binding ring, *m*, encircles the inner ring, holding the same in position and covering the joints therein. The joints between the inner and outer rings are or are intended to be perfectly steam-tight. Said rings *m n* are 60 duplicated and arranged in a series, as indicated in Fig. 1, the cuts in each contiguous ring being "broken" by the ring laterally adjacent. After the rings *m n*, I arrange a ring, *e*, preferably with sockets *f*, corresponding to the 65 recesses *r*. Said ring *e* is uncut, or is preferably so, and is equal in width to the space between the rod and the box, as shown in Fig. 1. The outer face of the said ring is made true and smooth, so that a perfectly steam-tight joint 70 will be formed between the said ring and the plate *a*. The rings *m n* do not completely fill the space between the box and the rod, but leave an amount of space sufficient to receive 75 the bar *p'*, and a spring, *t*, arranged in connection therewith. Within said space, at several points therein, are arranged said bars *p'* and springs *t*, the ends of said bars being arranged and working within the recesses and sockets *f* and *r*, and said springs bearing against the 80 side walls of the box.

The action of the device is as follows: The springs hold the several rings in close lateral engagement and against the plate *d*, and the springs and plates *p' t* hold the cut rings against 85 the rod. It is not necessary that the said springs be of any great strength, but of enough strength to hold the parts together. The steam, when the piston-head is driven from the stuffing-box, passes through the rod-aperture *v* into 90 the chamber back of the rings *m n*, and, bearing against said rings, holds them against the rod. In the reverse action of the piston-head the pressure of the steam will be removed and the springs *s t* will be sufficient to hold the 95 parts together. The joint between the plate *d* and parts *e e* being steam-tight, exit of steam is prevented at that point.

It will be apparent that the arrangement of

the rings m n allows any lateral action of the rod, and that the rings o and e may be formed to allow said action.

The joint between the plate d and parts c e , 5 above described, may be packed, if necessary, or ground, so as to be perfectly steam-tight, as above set forth.

Having thus described my invention, what I claim, and wish to secure by Letters Patent, is—

- 10 1. The combination, with the box a , of a packing composed of inner right-angular rings, n , and a binding-ring, m , surrounding the same, and means adapted to hold the said rings into operative connection with the rod, all as herein set forth and shown.
- 15 2. In combination, the solid rings e o and cut inner and outer rings, m n , and a spring adapted to hold said rings m n against the rod, substantially as herein set forth and shown.
- 20 3. The combination, with the box a , having

the plate d , secured against the end thereof, forming a steam-tight joint therewith, of the solid rings e o , right-angular ring n , binding-ring m , spring s , placed at the head of the box and tending to throw said rings forward against 25 said plate d , and mechanism adapted to hold the rings m n against the rod, as herein set forth and shown.

4. A piston-packing composed of a series of right-angular rings having a steam-chamber 30 between said series and the box, whereby the steam may force the rings against the rod, as set forth.

In testimony that I claim the foregoing I have hereunto set my hand this 9th day of 35 January, 1883.

SAMUEL ARMSTRONG.
